UNITED STATES PATENT OFFICE.

CARL A. RAUSCH, OF LEIPZIG-GOHLIS, GERMANY, ASSIGNOR TO THE FIRM OF FORTUNA-WERKE, SPECIALMASCHINENFABRIK, G. M. B. H., OF STUTTGART-CANNSTATT, GERMANY.

HIDE-CARRIER FOR BOARDING-MACHINES.

1,172,632.

Specification of Letters Patent.

Patented Feb. 22, 1916.

Application filed May 27, 1915. Serial No. 30,760.

To all whom it may concern:

Be it known that I, CARL A. RAUSCH, of 13 Roscherstrasse, Leipzig-Gohlis, in the Kingdom of Saxony, German Empire, civil 5 engineer, have invented certain new and useful Improvements in Hide-Carriers for Boarding-Machines, of which the following is a specification.

My invention relates to leather boarding 10 machines and more especially to the devices for carrying the folded-up hides to be rolled to and fro in these machines.

In order to secure an effective operation 15 of the boarding machines it is important to arrange within the fold of the hide to be boarded a partition plate as smooth and thin as possible. This partition, however, being put under a high stress both as regards 20 rigidity and strength, it has up to today proved difficult to provide a hide carrier fully corresponding to all requirements.

According to my invention the partition proper has the form of a band of steel or a like material, said band being tightly 25 stretched within a bow-shaped carrier and being adapted to be kept constantly tight by means of suitable stretching devices.

In the drawings accompanying this specification the preferred form of a hide carrier 30 according to my invention is shown in side elevation, partly in section.

In the machine frame *a* a bow-shaped carrier *b* is fastened. Between its free arms 35 preferably braced by a rod *c* a steel band *d* is stretched. Both ends of the band are pro-

vided with suitable mountings comprising screw-bolts *g* and cap-shaped nuts *h* resting against washers *i* interposed between them and the arms of the bow. By turning the nuts the band *d* can be stretched at will. 40

The bow *b* and rod *c* are preferably made of metal tubing.

I claim:

1. In a hide carrier for boarding machines, in combination, a thin and smooth 45 band of strong material and a bow shaped carrier adapted to keep said band in stretched condition.

2. In a hide carrier for boarding machines, in combination, a thin steel band and 50 a bow shaped carrier adapted to keep said band in stretched condition.

3. In a hide carrier for boarding machines, in combination, a thin steel band, a bow shaped carrier adapted to keep said 55 band in stretched condition and means arranged on said band for adjusting it.

4. In a hide carrier for boarding machines, in combination, a thin and smooth 60 band of strong material, a bow shaped carrier adapted to keep said band in stretched condition and a longitudinal stay rod adapted to brace the free arms of said carrier.

In testimony whereof, I affix my signature in presence of two witnesses.

CARL A. RAUSCH.

Witnesses:

RUDOLPH FRICKE,

ALICE DUNGER.
